[57] CLAIM

The ornamental design for an extension cord with multiple receptacles, as shown and described.

DESCRIPTION

FIG. 1 is a diagrammatic perspective view of the extension cord with multiple receptacles.

FIG. 2 is a left side elevational view thereof, the right side elevational view being a mirror image of the left side view. FIG. 3 is a top plan view of the extension cord with multiple receptacles.

FIG. 4 is a bottom plan view thereof.

FIG. 5 is a rear elevational view thereof; and,

FIG. 6 is a front elevational view thereof.
